CLAIM

The ornamental design for a steering wheel, as shown and described.

DESCRIPTION

This application contains subject matter related to the following co-pending U.S. design patent application:

Application Ser. No. 29/439,396, filed herewith and entitled "Steering Wheel".

FIG. 1 is a left perspective view of a steering wheel according to the design, the right perspective view being mirror symmetrical;

FIG. 2 is a left side view thereof, the right side view being mirror symmetrical;

FIG. 3 is a front view thereof; and,

FIG. 4 is a top view thereof.

The broken lines are for illustrative purposes only and form no part of the claimed design.
